UNITED STATES PATENT OFFICE.

WILLIAM H. CATER, OF CHICAGO, ILLINOIS.

METHOD OF SINKING, CLEANING, AND REMOVING WELL SCREENS.

Application filed March 17, 1923. Serial No. 625,738.

To all whom it may concern:

Be it known that I, WILLIAM H. CATER, a citizen of the United States, and resident of Chicago, in the county of Cook and State of Illinois, have invented certain new and useful Improvements in Methods of Sinking, Cleaning, and Removing Well Screens, of which the following is a specification.

10 In the sinking or driving of perforated or apertured well screens or casings, in their ordinary use and in their withdrawal from the earth, trouble is frequently encountered by reason of the clogging of the 15 holes of such screens or casings by gravel, sand, dirt and the like, which becomes more or less embedded therein, thus hindering or rendering inefficient the manipulation of the casing or the use of the well.

20 Accordingly, one object of the present invention is the provision of a simple and effective method of freeing or clearing or cleaning out such holes or apertures whereby the well may function more correctly 25 and actively, or whereby the casing may be more readily sunk or withdrawn as the case may be.

One operation by which the above-stated object of the invention may be fulfilled consists in subjecting the water which partially or wholly fills the casing to a very sudden and high pressure, which forces it out through the casing holes, thus temporarily washing or flushing outwardly the interfering or clogging dirt or earth, such pressure at the same time loosening or partially removing the earth just beneath the foot of the casing. This pressure is desirably imparted to the water, well known to be 40 substantially non-compressible, by dropping a weight on such body of water confined within the casing, and this is easily and readily accomplished by using the excavating pump itself and its load as the weight for performing the pressure-enforcing operation.

Another operation, by which the above-stated object of the invention may be fulfilled, consists in moving the weight quickly upward through the well screen, which causes the fine material lying adjacent to the outer side of the screen and more or

less clogging the openings thereof to flow into the well, allowing the coarser material to lie adjacent to the screen, and thereby 55 causing a large area of filtration and percolation outside the screen.

While each of these operations is effective to clean, and thus rejuvenate, to a considerable extent, a dirty and clogged screen 60 without the necessity of withdrawing it from the well, yet the screen is most efficiently cleaned, and the best rejuvenating results secured, by performing both of these operations in alternating relation. The first 65 mentioned operation, namely, applying a sudden pressure to the body of water within the screen, dislodges and more or less breaks up the earthy matter clogging the openings, driving it to the outside of the 70 screen; and the second operation, by producing an inward suction, draws the dislodged fine material into the well beneath the pump, by which latter it is picked up and ultimately discharged from the well. 75

A further object of the invention, which is attained by the operations above described, is the development of an underflowage of gravel formations existing in a vein. By subjecting the liquid to sudden 80 pressure, then passing the pump or other weight through the vein, and then raising the pump or weight swiftly, the fine material is caused to enter the well and be pumped out when cleaning. By repeating this method it is possible to draw all the fine material from that vein into the well, allowing the coarser material to lie adjacent to the well screen, which builds up a large area lying around the well casing. 90 By this method of operation, after the fine material has been removed there is built up a large filtering system around the well which means a lazy flowage and long life, as the fine sediment lying away from the 95 well will not be subject to such a high velocity when the water is traveling through, which would otherwise cause the screen to become clogged in a short time.

To enable those skilled in this art to have 100 a full and complete understanding of the invention and the various structural and functional advantages which accrue from its employment, I have illustrated in the

accompanying drawing, forming a part of this specification, a simple appliance for carrying out the preferred method.

In this drawing:—

5 Fig. 1 is a fragmentary central section through the well-casing and its associated excavating-pump; and

10 Fig. 2 is a perspective view of a small portion of the apertured, sheet-metal wall of the shell or casing.

15 Referring to the drawings, it will be perceived that such metal shell or screen 8, which may be of sections longitudinally secured together if desired, is desirably per-
20 forated or apertured by providing slits or openings 10 therein by reason of outwardly-deflected or outwardly-pressed strips 9 of the sheet-metal of which the casing is formed, and such shell or screen is provided
25 at its lower end with a cylindrical, sharp-edged foot or shoe 11, the casing or shell at its upper end, above the surface of the ground, being fitted or equipped at least temporarily with a weight 12 of any ap-
30 proved type, shown diagrammatically, to assist in the descent of the casing.

35 The pump employed in connection with such apertured screen or casing comprises a cylinder 13 of about the same diameter as the internal caliber of the casing, which cylinder at its lower end fits over and is secured to a base-ring 14 having a bottom edge notched or recessed at 15, 15 for the passage inwardly therethrough of water, earth, gravel, etc., such element 14 within the lower part of the cylindrical shell 13 being equipped with a hinged valve 16 disposed in an inclined relation when closed over the end of member 14 to facilitate its upward
40 opening movement under the suction action to which it is subjected.

45 Internally, the pump-cylinder accommodates a reciprocating, perforated or ported piston or plunger 17 mounted fixedly on the lower end of an upright rod or shaft 18 having an eye or loop 19 at its upper end for the attachment of an operating cable or chain, not shown.

50 A round, flexible, disk-valve 20, such as of leather or rubber, is positioned over the top, flat face of the plunger and is adapted to open and close the ports of the latter, depending upon the direction of movement of the parts, all as will be readily
55 understood.

A coiled cushion-spring 21 surrounds the rod or shaft just above the valve, as is clearly indicated.

60 At the top end of the pump, the rod or shaft 18 slides through a bearing-block 22 swiveled in the walls of the pump-cylinder, the latter being cut away at one side at 23 for a sidewise discharge of the pump's contents, during which operation the rod or
65 shaft 18, by reason of the turning of the

bearing-block, occupies a recess or slot 24 cut in the opposite side of the pump-cylinder.

To receive its load of earth, gravel or the like, the pump is lowered in the well inside 70 of the casing until the base-ring 14 rests on the earth at the bottom of the well, in which position it will be surrounded by the foot or shoe 11, and the piston or plunger 17 is permitted to descend, the valve 16 being 75 closed, until it reaches the lower portion of the pump.

Then the cable or chain, not shown, engaging the eye 19, is lifted, causing the rapid ascent of the piston or plunger, which creates a high degree of suction beneath it, thus unbalancing the air pressures and occasioning the opening of the valve 16 and the filling of the pump-cylinder beneath the piston with a mixture of dirt, gravel, water, 85 etc.

80 This piston is lifted to the limit of its upward movement so that the cushion-spring 21 engages the bearing-block 22, and then as the pump and its load are lifted bodily by 90 the further upward movement of the supporting-cable, the valve 16 closes and retains the load in the pump shell or cylinder.

95 When the screen is to be cleaned, after such loaded pump has been raised or ele-
100 vated a sufficient distance above the surface of the water in the apertured or perforated screen or casing, it is permitted to fall onto the body of liquid in such casing, creating a sudden and sufficient pressure in the liquid 100 to cause it to be forced outwardly through the perforations or holes of the casing or screen and also, at least in some cases, beneath the lower cutting edge of the shoe or foot 11, so that the screen is in large 105 measure freed from the earth bearing against it, and its descent under the action of the weight 12 is aided and facilitated, and also effecting the unclogging of the casing slits or apertures by the removal of the dirt 110 therefrom because of the sudden outward flow of water therethrough. This operation is preferably followed by a sudden upward raising of the pump through the screen, 115 which induces a strong inward suction caus-
120 ing the dirt and other fine material previously dislodged from the screen openings on the outer side of the latter to be sucked into the well below the pump. By repeating these alternate forcing and sucking opera-
125 tions, the apertures of the screen are very thoroughly cleared of fine dirt and sand, as well as the area immediately outside the screen.

130 Instead of forcing the casing downwardly at the same time that the pressure is imposed on the liquid by the falling weight, such screen or shell may be pulled upwardly, the sudden pressure imposed on the liquid facilitating such withdrawal action.

by reason of its temporarily washing away the dirt from and around the holes of the casing.

After the well has been completely sunk or completed, if the apertures become clogged or filled so that the operation of the well is somewhat inefficient, they may be readily cleaned or freed from the interfering matter by repeating the above described operations.

This invention is not limited and restricted to the precise and exact details presented because these may be modified within comparatively wide limits without departure from the heart and essence of the invention and without the sacrifice of any of its substantial benefits and advantages. It is to be clearly understood that the invention includes and comprehends each of the above described operations alone, but in its preferred form embraces both operations when performed alternately.

I claim:

1. The method of freeing the apertures of well-casings from clogging material to assist in the casing-shifting operation, consisting in subjecting the liquid in the well-casing to a sudden pressure which forces the liquid outwardly through such apertures, and substantially simultaneously submitting the casing to a force tending to shift it longitudinally in the earth.

2. The method of freeing the apertures of well-casings from clogging material to assist in the casing-shifting operation, consisting in subjecting the liquid in the well-casing to a sudden pressure by dropping a weight upon the liquid which forces the latter outwardly through the casing-apertures, and substantially simultaneously submitting the casing to a force tending to shift it longitudinally in the earth.

3. The method of sinking a well-casing consisting in subjecting the liquid in the well-casing to a sudden suction, and substantially simultaneously subjecting the casing to a downward pressure in the earth.

4. The method of freeing the apertures of well-casings from clogging material, which consists in alternately subjecting the liquid within the well-casing to a sudden pressure and a sudden suction.

5. The method of freeing the apertures of well-casings from clogging material, which consists in alternately dropping a weight upon the liquid in the well-casing to thereby force the liquid outwardly through the casing apertures, and rapidly raising said weight to thereby induce an inflow of the liquid through said apertures.

In witness whereof I have hereunto set my hand and seal.

WILLIAM H. CATER. [L. s.]
